ROCKING CHAIR

Walter S. Piper, Sheboygan, Wis.

Application January 7, 1939, Serial No. 249,746

2 Claims. (Cl. 155—54)

This invention relates to furniture and refers particularly to rocking chairs.

It is an object of this invention to provide an improved rocking chair which does not have the objections and disadvantages of the conventional rocker, in which the rocking members rest directly on the floor. To this end, the invention consists in the provision of a chair having a stationary leg structure from which the chair structure is movably suspended.

This style of rocking chair is not broadly new, but in all chairs of this nature heretofore in use, the construction has been such that the mechanism for joining the chair structure to the leg structure was so located that unless a valance was draped from the base of the chair structure, this mechanism was in plain view which, of course, is objectionable from the standpoint of appearance.

It is, therefore, an important object of this invention to provide a rocking chair of the character described which is so designed and constructed that the entire mechanism which movably mounts the chair structure on its legs and which, to assure the desired free swinging action and comfort, is completely concealed from view entirely without the need for a valance.

Another object of this invention is to provide a chair of the character described, which is so designed and constructed that the spring device which constitutes the mechanism for movably supporting the chair structure from its legs is disposed in the space defined by the base of the chair structure to thus permit a lower over-all height and improve the appearance of the chair.

With the above and other objects in view which will appear as the description proceeds, this invention resides in the novel construction, combination and arrangements of parts substantially as hereinafter described, and more particularly defined by the appended claims, it being understood that such changes in the precise embodiment of the hereindisclosed invention may be made as come within the scope of the claims.

The accompanying drawing illustrates one complete example of the physical embodiment of the invention constructed in accordance with the best mode so far devised for the practical application of the principles thereof, and in which:

Figure 1 is a side view of a rocking chair constructed in accordance with this invention with parts thereof broken away and in section; and

Figure 2 is a bottom view of the chair.

Referring now particularly to the accompany-

ing drawing, in which like numerals indicate like parts, the numeral 4 designates the chair structure generally which, as is customary, comprises a seat 5, a back 6, and arms 7. The lower portion or base 8 of the chair structure includes 5 side members 9 joined by front and back transverse members 10 and 11, respectively, and by a strong cross piece 12 positioned substantially midway between the front and back transverse members.

The entire structure is movably mounted on a leg structure indicated generally by the numeral 13. This leg structure consists of two parallel side rails 14 joined by front and back cross rails 15 and 16, respectively.

The side rails of the leg structure are preferably spaced apart a distance less than the spacing between the side members of the chair structure base so that the base may sink beneath the top of the leg structure. For the sake of appearance, the lower edges of the side members 9 and the top edges of the side rails 14 are correspondingly curved, but any configuration may be used as there is no actual rocking support.

Instead, the pair structure is suspended from 25 the leg structure by means of two spring devices indicated generally by the numeral 17. Each spring device is formed from a single length of a spring wire and includes a pair of coils 18 joined by a straight length of wire 19 and having spring 30 arms 20 extending forwardly and backwardly, the extremities of the spring arms being bent angularly. These angularly disposed ends of the spring arms are received in tubes 21.

The front ends of the spring arms 20 are hinged 35 to the adjacent front cross rail 15 of the leg structure by clips 22 and the rear ends of the spring arms 20 have a double hinge connection with the adjacent back transverse rail 16 provided by brackets 23 fixed to the rail 16 and 40 links 24 attached at one end to the ends of the spring arms and at their other ends to a rod 25 mounted in the brackets 23.

The straight lengths 19 of spring devices are anchored to the undersurface of the cross member 12 by clips 26.

With this construction, the chair structure is normally held in its position shown in Figure 1 but is free to descend a distance depending upon the weight of the occupant and to rock forwardly 50 and backwardly. A slight side motion is also permitted, which gives the effect of a floating support for the chair structure.

Particular attention is directed to the fact that the construction of the chair structure per-

mits the spring devices to be located above the lower edge of the side members 9. This disposition of the spring devices obviously allows the overall height of the chair to be less and obviates the necessity for providing a valance or any other means for concealing the supporting mechanism. This desideratum is achieved through the use of an arched support 27 for the seat of the chair. This seat support is resilient and consists of a plurality of parallel rows of wire springs 28 having their ends anchored to the front and back cross members 10 and 11.

Each wire spring has a zigzag formation to provide resiliency but the combined strength of these springs is sufficient to at all times maintain an adequate arch to the seat support to provide the necessary space for the spring devices.

From the foregoing description taken in connection with the accompanying drawing, it will be readily apparent to those skilled in the art that this invention greatly improves the construction of a rocking chair of the type having a stationary leg structure and that it adds materially to the appearance of the chair by obviating the necessity for special means for concealing the spring device which supports the chair proper from the stationary leg structure.

What I claim as my invention is:

1. In a rocking chair of the type having a stationary leg structure including front, rear and side rails and a chair structure mounted thereon by means of a spring device which permits descent of the chair structure as well as rocking motion, the combination of: means in the bottom of the

chair structure to which the spring device is secured; and rigid front and side walls on the frame of the chair structure extending substantially below the level of said means sufficiently to conceal those portions of the spring device located above the leg structure, said means to which the spring device is secured extending between the chair frame side walls, the lower edges of said rigid side walls being convexly arched so as to enable rocking of the chair structure to extreme positions without having the rigid side walls contact the floor even when the chair structure is caused to descend to an extreme position.

2. In a rocking chair of the type having a stationary leg structure including front, rear and side rails and a chair structure mounted thereon by means of a spring device which permits descent of the chair structure as well as rocking motion, the combination of: a resilient seat support on the frame of the chair structure arched from front to back to provide substantial space beneath the bottom of its medial portion and the lower edges of the side walls of the frame of the chair structure; and a strong cross member joining the side walls of the chair structure frame a substantial distance above the lower edges thereof and in said space, said cross member having the spring device secured to its undersurface, and said side walls of the frame of the chair structure extending below the level of said transverse member sufficiently to conceal those portions of the spring device located above the leg structure.

WALTER S. PIPER.
